MOLDING APPARATUS

John W. Lowell, Chicago, Ill., assignor to
Benedict Stone Products Company, Chicago,
Ill., a Corporation of Illinois

Application May 9, 1932. Serial No. 610,238

9 Claims. (Cl. 25—41)

My invention relates to method of and apparatus for making precast concrete and has particular reference to a method of and means for suspending a mold while the concrete therein is packed by vibrations imparted to the mold to take the place of tamping.

The present application is a continuation in part of my prior application Serial No. 394,935, filed September 25, 1929, for Molds, for which this application is substituted, and the drawings of the present application are transferred from said prior application.

Another and further object of my invention is the provision of a method of and apparatus for making concrete, in which molds, supported by flexible suspension means, are used and vibrations imparted to the said molds and confined to the molds without being scattered to the support means.

20 Another and further object of my invention is a method of making precast concrete by packing the green concrete in molds by imparting vibration to the molds while supporting the molds in such manner that the vibrations are confined to the molds, and the molds are uniformly vibrated in order that uniform binding of the concrete be secured, or vibrations may be imparted directly to the concrete in the molds.

In making precast forms of concrete the usual practice has been to fill the molds with wet or green concrete and tamp the concrete into the molds to secure firm bonding of the blocks or slabs or other objects after the concrete has set. Many objections have been found in this practice, however, particularly owing to the inability to uniformly tamp the concrete or compact it to sufficient density. Various vibratory means have been used for the tamping or packing of the green concrete and when such methods are used it has been the common practice to mount the molds upon rigid supports, such as floors, tables, frames or the like. It has been extremely difficult to keep the frames fastened to a floor owing to the rapid vibration which it is necessary to impart to the molds, and if the frames, within which the molds are mounted, are not securely fastened to the floor, they creep over the floor and will not remain placed in proper position. If the molds are fastened to a floor and vibrators attached to them they are disagreeably noisy in operation, so much so, that it is almost impossible for workmen to operate them, particularly if a number of molds are secured together in one room, and the vibrators are partially neutralized or deflected so that the molds are not evenly vi-

brated, and the concrete is not uniformly packed.

To overcome these objections I have devised suspension means for the mold, including a flexible sling, which will permit the mold to be tilted to various positions for the purpose of forming precast concrete slabs of varying thickness of layers of concrete, and which also may be utilized for the handling of the mold in the plant after the concrete has set or after it has been packed, and which absorb the vibrations so that the vibratory movements are confined to the mold.

Another object of the invention is the provision of an improved mode of mounting electric vibrators of the type having an eccentric weight on the motor shaft so that the rotation of the eccentric weight may induce vibrations or oscillations of the entire motor casing with respect to the mold, these vibrations being transmitted to the mold through a resilient and flexible motor hanger which is carried by a support secured to the mold by clamping devices.

Another object of the invention is the provision of an improved molding apparatus which is adapted to utilize more effectively the vibrations which may be induced by means of a motor having an eccentric weight on its shaft.

These and other objects will be more fully and better understood by reference to the accompanying sheets of drawings, and in which

Fig. 1 is a side elevational view of a mold employing my improved suspension means;

Fig. 2 is an end elevational view of the mold illustrated in Fig. 1;

Fig. 3 is a side elevational view of a modified form of mold and suspension means;

Fig. 4 is a top plan view of the mold illustrated in Fig. 3 on the line 4—4;

Fig. 5 illustrates another modified form of mold for making large flat slab structures; and

Fig. 6 is a top plan view of the mold and suspension means illustrated in Fig. 5.

Referring now specifically to the drawings, in which like reference characters refer to like parts throughout, a rectangular shaped frame 10 is illustrated having a pair of shafts 11 and 12 mounted therein, upon which rollers 13—13 are mounted at each of their ends, and which engage tracks 14, 14, which are suitably mounted or supported on a building structure in any desired manner. The frame 10 may be operated manually or may have an electric motor connected thereto after the usual fashion of cranes of this character.

Mounted upon the frame 10 is a carriage 15 having a motor 16 mounted thereon, with wheels 16a,

16a on said carriage for engagement with a pair of tracks 16b mounted in the frame 10, and is capable of longitudinal movement therealong. The motor 16 is directly connected to a hoisting reel 17, around which a cable 18 operates. To the free end of the cable 18 a clevis 19 is attached, which in turn engages a U-shaped member 20 having a pair of flexible loops 21 and 22 mounted therein, and which extend around each end of a frame 23, composed of a pair of parallel extending bars 24, 24 and cross lots 26 and 27 having suitable spacers thereon, with a mold 25 being mounted on said frame 23.

The flexible loops or straps 21, 22 may be made of leather, rope, steel strap or steel cable, and they constitute a flexible form hanger for the mold or form 25. The base of the mold or the supporting framework for the mold constitutes a support, which support is provided with clamping members 32 for engaging the form, particularly the flanges of the angle irons 31 carried by the mold and clamping the mold to the supporting framework so that the mold will not move around under the influence of vibration upon its supporting framework. The relatively long and slender parallel extending bars 24 are naturally resilient and sufficiently flexible to permit them to flex or bow under the vibrating influence of the vibrating apparatus 28.

30 In some cases the bars 24 were found to be too flexible, so that they permitted too wide a range of amplitude of vibration of the motor, in which case rubber pads were placed between the bars 24 and the bottom of the mold to reduce the amplitude of vibration of the motor and reduce the amount of flexure of the resilient and flexible bars 24. The bars 24 are preferably made sufficiently flexible to permit the range of amplitude of vibration desired, and the necessity for the rubber pads may be eliminated by making the bars 24 slightly thicker for the longer spans of forms, but in every case the bars 24 must be sufficiently flexible to permit vibration of the motor with respect to the form.

45 A vibrating apparatus 28 is mounted upon the frame 23 by being secured to bars 24, 24 intermediate the ends thereof and preferably centrally located with respect thereto by means of U-shaped members 24a. This vibrating apparatus, as illustrated, comprises an electrically operated motor having an unbalanced rotor therein which, when operated, is designed to impart a vibratory action to the mold 25. This vibrating apparatus may be electrically or steam operated, or in any manner to impart vibration to the mold 25, to cause a settling or packing of the green concrete after it is placed in the mold.

50 The inherently flexible and resilient rods or bars 24 constitute a flexible motor hanger for the motor, the ends of which are connected to the support or framework by means of the clamping members 32. Various forms of flexible motor hangers may be employed, provided the hanger is so arranged that its flexibility is not great enough to prevent the transmission of the motor vibrations to the mold, but the flexibility should be sufficient to permit the motor to vibrate with respect to the mold.

55 It will be noted that the motor provided with the unbalancing weight is secured to the motor hanger intermediate the points of connection of the motor hanger 24 to each end of the mold by means of the clamps 32. Vibrations are thus transmitted to the mold from each end of the motor hanger. The modes of connection of the

motor hanger bars to the mold may be made adjustable, and the flexibility or resiliency of the motor hanger bars 24 may be adjusted, if desired. The spacing members 36 which connect the bars 24 are preferably adjustably mounted upon the bars 24 for longitudinal adjustment with respect to the bars so that the clamping members 32 may be slid back and forth to bring them into proper position to clamp the motor hanger on forms of different length or width.

55 The mold 25 is a rectangular shaped device, open at its top and closed on the sides, ends and bottom, and has its bottom plate extending beyond the end walls of the mold, forming projections 29 and 30, upon which angles 31, 31 rest, these angles also engaging the end walls of the mold 25. A pair of L-shaped clamping members 32, 32 are provided, which have a threaded member 34 projecting thereinto, with a crank 35 at the lower end thereof and a spacing member 36, which engages the under side of the bars 24, 24. By tightening the cranks 35, the mold 25 is clamped tightly upon the frame 23, so that the mold is firmly held in position and suspended upon the flexible members 21 and 22.

60 The motor may consist of an ordinary electric motor rotating at about 3690 revolutions per minute and having at one or both of its ends a radially extending arm fixedly secured to the end of the shaft and provided with an eccentric weight preferably located in the motor casing.

65 Loops 37, 37 are provided around the flexible members 21 and 22 adjacent to the member 20, so that if it is desired to tilt the mold 25 sideways in order to produce a precast piece of concrete which is thicker at one side than at the other, the mold 25 is thereby tilted to one side so that the flexible members 21 are slightly longer on one side than on the other and the loops 37 are thereupon slipped up against the member 20 so that the suspension members 21 and 22 are held in proper position so that the mold is slightly tilted. If it is desired to incline the mold 25 with this form of device so that one end is higher than the other, a rope or other flexible 70 fastening means is secured to one end and the device tied to the side of a building or to the track, as may be desired, so that it is turned around its point of suspension on the member 20.

75 In Figs. 3 to 6, inclusive, a form of mold suspension means is provided, in which a single mold is suspended from two or more hoisting units. This apparatus is desirable for large sizes of precast stones or slabs, and also permits greater flexibility in the handling of the molds. One 80 form of apparatus consists of a pair of frames 10 and 10a, which are mounted upon the tracks 14, 14, which are supported on a building in any suitable manner. The frame 10a is constructed in exactly the same manner as the frame 10, a detailed description of which has been given heretofore. Hoisting units 15 and 15a (which are duplicates of each other in construction) are mounted upon the frames 10 and 10a and have cables 40 and 41, respectively, connected to the hoisting drums, to which rings 42, 42 are connected at their lower ends. Flexible members 43 and 44 are provided, which extend around the mold 25 and the frame 23 at each of its ends, and extend through eyelets formed in hooks 45, 45 which engage the rings 42, 42. The members 43 and 44 have loops 37, 37 thereon which, through friction, hold the members 43 and 44 in adjusted positions for the purpose of canting the mold if desired.

In this form of device, if it is desired to tilt the mold longitudinally, one end is raised slightly higher than the other and through the hoisting mechanism, thereby tilting the mold a slight 5 degree.

In Figs. 5 and 6 a device is illustrated for making precast slabs of large dimension, in which a mold of slightly different form is shown and in which four hoisting elements are employed. The 10 frames 10 and 10a are employed, which are mounted upon the rails 14, 14. The frame 10 has a pair of hoisting carriages 15 and 15b mounted thereon, each of these carriages having motors mounted thereon, with hoisting drums connected thereto, to which cables 47 and 48 are connected. The frame 10a has a pair of carriages 15a and 15c mounted thereon, upon which motors and hoisting drums are mounted, to which cables 49 and 50 are connected.

20 Two pairs of longitudinally extending rails 24, 24 are provided, each pair being secured together by bolts 26 and 27 at each of their ends, with spacers mounted on said bolts. Clamping devices comprising clamp members 32, 32, threaded members 34 and cranks 35, are provided, which engage saddles 36, 36 which space each pair of bars 24, 24, thereby clamping the mold 51, which differs slightly in form from the mold 25 heretofore described, in position. A pair of 25 vibrating devices 28, 28 are mounted on each pair of rails 24, 24 in spaced relation with each other, and preferably in such position that one vibrator is approximately at one-quarter of the distance from the ends of the bars 24.

30 The mold 51 is provided with a bottom plate 69, which projects somewhat beyond the sides of the mold and has eyes 53, 53 secured thereto near each of its corners, to which the cables 47, 48, 49, and 50 are secured, thereby suspending the mold 35 from the hoisting apparatus. In this form of device each of the hoisting mechanisms is operable independently of the other, so that the mold may be tilted from side to side, or either of the ends elevated above the other, as may be desired. 40 The vibrating devices are placed under the mold preferably somewhere near the center of each quarter section of the bottom of the mold, but in this respect they may be placed in various positions and operated either in synchronism with each other or independently for imparting vibration to the mold.

45 In operation of the device, the molds are filled with green concrete and are thereupon secured to the longitudinally extending bars 23 and 24 and clamped firmly in position upon these bars. They are then suspended from the flexible members 21 and 22 and vibration imparted to the mold through the member 23 until the green concrete has been caused to settle in the mold to the degree desired, the mold being held in suspended position while vibration is imparted to it. Because the suspension straps are flexible, the vibration is imparted only to the mold and not to the suspension means, and therefore the objection to the molds in a fixed position upon a floor is avoided, both with respect to the creeping of the molds and objectionable noises.

50 In all of the embodiments described, the motor vibrator having the eccentric weight is mounted upon relatively long resilient and flexible metal rails, rods, bars or straps secured at each end to the mold supporting frame or to the mold itself.

55 The flexibility of the rails, rods, bars or straps may also be diminished by placing them under tension, but if the motor hanger is properly pro-

portioned in size and length to provide the proper flexibility and resiliency, no adjusting devices need be employed.

The operation of the vibrating apparatus is explained as follows with reference to Figs. 5 and 6, for example. The mold 51 is supported upon a framework comprising the longitudinally extending frame members 51 and transversely extending frame members 31, the framework being in turn supported by the flexible cables 47, 49 at 60 each of the four corners. The mold and framework are therefore free to vibrate under the influence of the vibrators, which are preferably located at the points of the greatest amplitude of vibration on the hangers 23, 24. For example, when only one vibrator is employed, it may be located midway between the ends, but when two vibrators are employed on each hanger, they may be located one quarter of the length of the form from the end of the form.

65 The vibrators 28 are carried in depending position from the relatively long flexible and resilient metal rails 23, 24, which are secured together at their ends by spacing members and provided with the clamping members 32. The ends of the motor hanger rails are secured to the form by the clamping engagement of the clamps 2 with the angle irons 31 thus also serving to clamp the form to the framework 51, 31.

70 The motor vibrator being provided with a relatively small eccentric weight, when the eccentric weight is rotated, the inertia of the eccentric weight tends to cause the motor to move in an orbit which is opposite in direction to that of the rotation of the eccentric weight.

75 The range of movement of the motor with respect to the range of movement of the eccentric weight bears a relation which varies inversely as the masses of the eccentric weight and the motor. Therefore, the amplitude of vibration of the motor is much less than that of the eccentric weight, but the motor possesses a greater mass and has the capability of transmitting its vibration more effectively to the mold on account of the greater mass of the motor and consequent greater intensity of its vibrations.

80 If the motor were unsecured or freely suspended, it would oscillate in a circular orbit, but as the motor is carried by a resilient and flexible hanger rail it has a greater freedom of movement in the direction in which the rail will flex or bend and has relatively little freedom of movement in the direction of the length of the rail. Therefore, the resilient and flexible rail permits the motor to vibrate up and down in Fig. 3 or 85 Fig. 5, and the greatest amplitude of vibration of the motor is in a vertical direction, although there is a smaller component of vibration in a horizontal plane, caused by the tendency of the motor to also vibrate the rails in the direction of their 90 length.

85 The resilient and flexible supporting rails 23, 24 give the motor vibrations a predetermined directional characteristic in a vertical direction, and these vibrations are transmitted to the mold 95 25 or 51 through the attachment of the motor hanger to the mold at its ends. The amount of flexure of the resilient rails 23, 24 depends upon their relative stiffness, and if the rails are made too slender or too long for their thickness, they 100 will flex too much and tend to dissipate the vibration of the motor without transmitting it to the mold 25, 51.

105 The motor hanger is therefore preferably proportioned in size so that its flexure is sufficient 110

to give the motor the amplitude of vibration desired, which is a matter of a fraction of an inch.

The vibration of the motor vibrator in a vertical plane, in Fig. 3, for example, tends to bow the hangers 23, 24 slightly, which has a tendency to shorten their length between the points of securement of the hangers on the mold. This tendency toward shortening is, however, resisted by the supporting framework and by the mold, which tend to tension the hangers as the deflection from a straight line increases. Obviously the inherently resilient and flexible hangers may be made stiffer either by increasing the tension or by increasing their cross sectional area.

15 After the setting process has been performed by the vibrating apparatus, the hoisting mechanism is used to convey the precast stone or block of concrete to any point desired, where it is removed from the mold or is allowed to set until 20 such time as the mold can be removed from the stone. The mold is readily removable from the longitudinally extending bars, so that a new mold can be secured upon the bars an the operation repeated.

25 The operation of the form supports described in Figs. 3 to 6 inclusive is substantially the same as that heretofore described, with the exception that these devices allow for the tilting of the molds with respect to end-to-end operation, or 30 canting of the molds from side to side. In the manufacture of precast blocks of concrete it has become the practice to form an exceedingly dense close surface on one side of the block and complete it with a different mix of concrete. It may 35 become desirable to have this layer formed more thickly at one side of the block than on the other, so that it is necessary to tilt the mold during the operation.

40 In the making of precast concrete or building stone that has become known in the building trade, a surface layer of varying color is also sometimes used and the balance of the building stone completed with an ordinary form of concrete. In applying these thin layers of concrete 45 they are usually applied to the bottom of the mold and the balance of the filling material superimposed upon the first layer of material. The outer surface of the stone is formed usually in a plain surface, while the inner side of the stone may 50 be of varying contour and thickness, which can be secured by tilting or canting the molds, as may be desired.

55 It will thus be observed that I have provided an improved molding apparatus, including an improved mode of resilient support for vibrators on the mold for increasing the effectiveness of the vibrating apparatus. When a vibrator having an eccentric weight is clamped fixedly to a relatively heavy and stiff form, the relatively small eccentric weight produces but very little effect in the 60 form of vibrations transmitted to the form, but when the vibrator is resiliently mounted upon resilient members which are sufficiently flexible to permit a flexure of the hanger with respect to the form, the effectiveness of the motor vibrator is increased many fold by virtue of the fact that the 65 mass and inertia of the entire motor are brought into play to react against the mold through the resilient support.

70 While I have described more or less precisely the details of construction, I do not wish to be understood as limiting myself thereto, as I contemplate changes in form and the proportion of parts and the substitution of equivalents as circumstances may suggest or render expedient

without departing from the spirit or scope of my invention.

Having thus described my invention, what I claim is new and desire to secure by Letters Patent of the United States, is:

80 1. In an apparatus for vibration of concrete, the combination of an electric motor provided with an unbalancing weight adapted to be rotated by the motor shaft, a resilient support for said motor, clamping members carried by the opposite ends of said resilient support and adapted to clamp a concrete form, and flexible means for suspending said concrete form, motor and support whereby said motor is adapted to place said concrete form in a state of high frequency vibration.

85 2. In an apparatus for vibration of concrete, the combination of an electric motor provided with an unbalancing weight adapted to be rotated by the motor shaft, a resilient support for said motor, clamping members carried by the opposite ends of said resilient support and adapted to clamp a concrete form, and flexible means for suspending said concrete form, motor and support whereby said motor is adapted to place said 90 concrete form in a state of high frequency vibration, said flexible means comprising tension members for supporting the opposite ends of said concrete form, and selective power actuated means for lifting one end or the other of said concrete 95 form through said flexible means to effect a predetermined distribution of concrete in the form under vibration.

100 3. In an apparatus for vibration of concrete, the combination of an electric motor provided with an unbalancing weight adapted to be rotated by the motor shaft, a resilient support for said motor, clamping members carried by the opposite ends of said resilient support and adapted to clamp a concrete form, and flexible means 105 for suspending said concrete form, motor and support whereby said motor is adapted to place said concrete form in a state of high frequency vibration, said flexible means comprising a plurality of tension members separately secured to 110 spaced points on said support, and selective power actuated means for exerting force on any of said tension members whereby various parts of said form may be lifted and said form may be tilted into any of a multiplicity of different planes to 115 effect a predetermined distribution of concrete in the form under vibration.

120 4. In an apparatus for high frequency vibration of concrete, the combination of a concrete form having a laterally projecting securing flange 125 at opposite sides of the form, with a framework comprising a longitudinally extending resilient metal member, clamping means at each end of said framework for securing said member to the securing flange of said form, and an electric motor 130 vibrator having an eccentric weight carried by the shaft of said motor, said vibrator being carried by said resilient longitudinally extending member whereby said eccentric weight is 135 adapted to place said concrete form in a state of 140 vibration.

145 5. In an apparatus for high frequency vibration of concrete, the combination of a concrete form having a laterally projecting securing flange at opposite sides of the form, with a framework comprising a longitudinally extending hanger clamping means at each end of said framework for securing said member to the securing flange of said form, and an electric motor vibrator having an eccentric weight carried by the shaft of 150

said motor, said vibrator being carried by said longitudinally extending hanger whereby said eccentric weight is adapted to place said concrete form in a state of vibration, and a plurality of 5 flexible members for supporting said framework, form and motor in a state of suspension whereby said concrete form may be vibrated without restraint.

6. In an apparatus for vibrating concrete, the 10 combination of a concrete form with a supporting framework, means for securing said framework to said form, flexible means for suspending said framework from a support for free vibration without restraint, said framework comprising an 15 elongated longitudinally extending resilient motor support, an electric motor, and an eccentric weight carried by the motor shaft, said motor being supported by said longitudinally extending resilient motor support at the point of its greatest 20 amplitude of vibration.

7. In an apparatus for vibrationg concrete, the 25 combination of a concrete form with a supporting framework, means for securing said framework to said form, flexible means for suspending said framework from a support for free vibration without restraint, said framework comprising an elongated longitudinally extending resilient motor support, and a pair of electric motors, each having 30 an eccentric weight carried by the motor shaft, said electric motors being carried by said longitudinally extending resilient member at

points of maximum amplitude of vibration of said resilient member.

8. In an apparatus for high frequency vibration of concrete, the combination of a pair of longitudinally extending tracks with a framework having supporting and guiding rollers engaging said tracks, and forming a longitudinally moving carriage with a transversely moving carriage having supporting and guiding rollers engaging said framework, said framework forming a transverse track, a motor having a hoist drum carried by said carriage, a flexible member wound on said drum and depending therefrom, a plurality of diverging flexible members carried by said first-mentioned flexible member, said diverging flexible members supporting a concrete form, a resilient member secured to said concrete form, and an electric motor having an eccentric weight carried by said resilient member and adapted to place said concrete form in high frequency vibration.

9. A method of treating concrete which comprises placing green concrete in a mold, suspending the mold by flexible tension members for free movement, subjecting the mold to high frequency vibrations while so suspended to improve the characteristics of the concrete and tilting the mold by means of said tension members to control the effect of said vibrations and effect a more perfect filling of the mold.
